UNITED STATES PATENT OFFICE.

WILLIAM H. COLEIN, OF BALTIMORE, MARYLAND.

SMOKE-CONSUMING ATTACHMENT FOR BOILER-FURNACES.

No. 841,074.

Specification of Letters Patent.

Patented Jan. 8, 1907.

Application filed April 23, 1906. Serial No. 818,220.

To all whom it may concern:

Be it known that I, WILLIAM H. COLEIN, a citizen of the United States, residing at Baltimore city, in the State of Maryland, have 5 invented certain new and useful Improvements in Smoke-Consuming Attachments for Boiler-Furnaces, of which the following is a description, reference being had to the accompanying drawings, and to the letters of 10 reference marked thereon.

My invention relates to improvements in steam-boiler furnaces, and particularly to an attachment therefor for accomplishing thorough combustion and preventing the discharge of smoke and soot in firing up.

The invention is shown as applied to various types of boilers and may with proper changes in mechanical details be applied to any type of boiler-furnace; and it consists in 20 providing an attachment for delivering steam in the rear of the bridge-wall of a furnace into the combustion-chamber, said steam-jet being controlled by a valve, preferably arranged at the front of the furnace 25 within convenient reach of the operator, the steam being directed into the combustion-chamber in such a way as to first form a cloud to check or hold in suspension the products of combustion and volatile particles arising from the fire when the coal is first 30 put on, and yet blowing in the general direction of the draft toward the stack, so as to increase the draft, and finally acting to clean the tubes.

35 I have found in practice that by the use of this attachment on a Heine boiler at the Baltimore federal building I am able to do away with the smoke nuisance, effect a saving of about a ton of coal per day, and to keep the 40 boiler-tubes practically clean and free from soot and dust.

The invention is illustrated in the accompanying drawings, in which—

Figure 1 is a sectional side view of a Heine 45 boiler of the usual type provided with my invention. Fig. 2 is a similar view illustrating the application of my invention to a Babcock and Willcox boiler. Fig. 3 is a horizontal section of the lower part of Fig. 2. Fig. 4 50 illustrates the application of the invention to a Scotch marine boiler, and Fig. 5 to a horizontal return tubular brick-set boiler.

55 Referring first to Fig. 1, this illustrates the ordinary Heine boiler, and it is not necessary to specifically describe it, except to state that A is the furnace; B, the bridge-wall; C, the

combustion-chamber, and aa the usual baffle-plates.

Steam is led from the steam-chamber to the vertical pipe b and thence to the horizontal pipe c, which extends to the rear of the boiler and supplies the jets d with steam, these jets extending through the hollow stay-bolts e in the rear wall of the boiler. The cock f controls the steam-supply to the jets, 60 and it is located at the front of the boiler and within easy reach of the operator. The jets d are so located that they discharge the steam beneath the top baffle-plate and in the space above the rear of the combustion-chamber.

The operation is as follows: When the attendant desires to fire up and before raking the fire or throwing on coal, he opens the cock f and allows steam to enter the combustion-chamber. He then throws on coal or rakes, as desired, and the steam acts to prevent escape of smoke and aids in combustion, increases the draft, and helps keep the tubes clean.

The action as I understand it is as follows: 80 When the steam enters, it expands, for an interval opposes the movement of the products of combustion, and forms a cloud which checks and holds in suspension the products 85 of combustion. By its force it also increases the draft, and as it becomes more highly heated it aids in combustion and also by its force tends to keep the tubes clean.

As soon as the stirring up of the fire is ended or enough coal has been put on and the fire begins to burn properly and danger of smoke is over the cock f is closed.

Figs. 2 and 3 show the application of the invention to boilers of the Babcock & Willcox type, in which, however, the pipe c extends from the front of the boiler to the rear of the bridge-wall and the jets supply steam in the manner shown in Fig. 2. In this instance the steam as it enters expands against 190 the products of combustion coming down between the baffle-plates a' a' and acts, further, in the manner described in connection with the boiler shown in Fig. 1.

Figs. 4 and 5 illustrate the application of 105 the invention to two well-known types of fire-tube boiler—viz., the Scotch marine boiler and the horizontal return tubular brick-set boiler.

I am aware that it is not new to inject 110 steam into a boiler-furnace to aid in combustion by blowing it into the fire-box in the di-

rection of the draft or to check combustion by blowing steam into the fire-box down into the fire to check too speedy combustion. I am also aware that it has been heretofore proposed to extend steam-jet tubes into the tubes of boilers for the purpose of cleaning the same, and I do not claim such as my invention. I believe, however, that I am the first to inject steam into the combustion-chamber of a boiler-furnace in such a manner that it first strikes the products of combustion in a direction substantially contrary to that in which they are moving, forms a cloud or curtain to check and hold them momentarily in suspension, and then mingles with the products of combustion, aids in the draft, and also serves while it is performing these other functions to keep the boiler-tubes clean.

Having thus described my invention, what I claim as new, and desire to secure by Letters Patent, is—

1. In combination with a boiler-furnace having a combustion-chamber and a bridge-wall separating the combustion-chamber from the fire-box, means for supplying live steam to the combustion-chamber, said means being so arranged that the flow of the steam is across the path of the products of combustion, but in the general direction of the movement thereof, thus forming a cloud or curtain in a direction against the passage of the products of combustion but aiding in the draft.
2. In combination with a boiler-furnace having a combustion-chamber and a bridge-wall separating the combustion-chamber from the fire-box, means for supplying live steam to the combustion-chamber, said means being so arranged that the flow of the steam is across the path of the products of

combustion, but in the general direction of the movement thereof, thus forming a cloud or curtain in a direction against the passage of the products of combustion but aiding in the draft, said steam being supplied with such force as to aid in cleaning the tubes and boiler-heating surface; substantially as described.

3. In a boiler-furnace in combination with the water-tubes and baffle-plates, a combustion-chamber, means for supplying live steam to the combustion-chamber, said means being so arranged that the steam is directed between the baffle-plates in the general direction of the draft, but across the path of the products of combustion, forming a cloud or curtain against the passage of the products of combustion, but also aiding in the draft; substantially as described.

4. In a boiler-furnace having baffle-plates extending in the direction of the tubes, steam-jets extending through the rear wall thereof and arranged to deliver live steam in the upper rear portion of the combustion-chamber in line with the tubes and across the path of the products of combustion and in the general direction of the draft, whereby a cloud or curtain is formed to envelop the products of combustion, the consumption thereof being aided and the tubes and boiler-heating surfaces kept clean, means located at the front of the boiler to control the steam-supply and a pipe extending from front to rear of the furnace to supply the steam-jets.

In testimony whereof I affix my signature in presence of two witnesses.

WM. H. COLEIN.
